US0D1111169S

(12) **United States Design Patent** (10) **Patent No.:** **US D1,111,169 S**
(45) **Date of Patent:** **** Feb. 3, 2026**

(54) **MOBILE IMAGING DEVICE**

(71) Applicant: **KONINKLIJKE PHILIPS N.V.**
Eindhoven (NL)

(72) Inventor: **Hyelin Lee**, Amsterdam (NL)

(73) Assignee: **KONINKLIJKE PHILIPS N.V.**
Eindhoven (NL)

(**) Term: **15 Years**

(21) Appl. No.: **29/878,388**

(22) Filed: **Jun. 21, 2023**

(30) **Foreign Application Priority Data**

(57) **CLAIM**

The ornamental design for a mobile imaging device as shown and described.

DESCRIPTION

FIG. 1 is a perspective view showing a mobile imaging device design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines illustrate portions of the mobile imaging device and form no part of the claimed design.

1 Claim, 7 Drawing Sheets
